WETTING-OUT-, WASHING-, CLEANSING-,
LATHERING-, AND DISPERSING AGENTS

No Drawing. Application March 16, 1933, Serial
No. 661,088. In Germany March 18, 1932

13 Claims. (Cl. 260—151)

The present invention has for an object the provision of improved wetting-out, washing-cleansing-, foaming- and dispersing agents. The wetting-out and emulsifying agents suitable for washing and cleansing purposes hitherto employed include sulphuric acid esters of the higher molecular fatty alcohols as well as higher molecular alkyl sulphonate acids in their original state or in the form of their neutralization products. Compared with the aforesaid esterlike sulphuric acid derivatives, it is true that the salts of the alkyl sulphonate acids distinguish themselves by extremely increased stability, but in the cold they are much less soluble so that their employment is limited to operations which can be carried out at higher temperatures, e. g., at temperatures of more than about 60° C. Moreover from experience to date, it appears that the feel, i. e., the softness and pliancy of the textiles treated with sulphonate acid salts is not as satisfactory as in the case when materials are treated with sulphuric acid ester.

Now it has been found that the alkyl ethers of the hydroxyalkylsulphonate acids formed with higher molecular alcohols, compared with the said alkylsulphonate acids, are of a better solubility in the cold, and besides possess good stability against acids, lime and magnesia salts. These compounds are therefore preferable for use for textile-chemical operations to be carried out at lower temperatures, e. g., for the cleansing of wool and silk, for the dyeing of artificial silk and the like.

These new compounds are formed by the alkoxylation of mono-hydroxy- or poly-hydroxy-alkylsulphonate acids with higher molecular fatty alcohols, e. g., by the alkoxylation of hydroxyethane-sulphonate acid or di-hydroxypropanesulphonate acid.

In accordance with the preferred procedure one commences with glycidic compounds such as, e. g., ethylene oxide or propylene oxide; one breaks down the ethylene oxide ring by alkoxylation and forms at the same time a hydroxyl group. The hydroxyl group after esterification with halogen hydracid is in turn replaced by the sulphonate acid group. These transformations are based on the following reaction equations:

There is still a simpler way of obtaining the new compounds, viz., by causing epichlorhydrine

to react with fatty alcohol mixtures in the presence of a small amount of sulphuric acid and with the aid of an autoclave and a slight excess of sodium sulphite, converting the reaction mixture obtained from the higher boiling components by washing with water and by fractional distillation in vacuo into sulphonate acid derivatives. Alkyl-chloroethylethers more difficult to prepare may be converted in the same manner with sodium sulphite into sulphonate salts of similar properties.

By "higher molecular" fatty alcohols suitable for the manufacture of the described products, I mean the aliphatic alcohols with at least 8 carbon atoms in the molecule and the naphthenic alcohols. Examples of suitable aliphatic alcohols are dodecyl-, myristyl- and cetyl alcohol and the alcohol mixtures obtained by high pressure reduction from natural greases such as cocoa fat and palm kernel oil. Unsaturated alcohols such as oleyl alcohol and its homologues are, however, likewise to be taken into consideration. Polyhydroxy saturated or unsaturated alcohols may also be used, such as hydroxystearyl alcohol or ricinoleyl alcohol (dihydroxyoctadecene) obtained by reducing castor oil according to the reduction method of Bouveault and Blanc.

The new products, in the form of the alkaline salts, comprise crystalline masses of excellent capillary active properties. In the following a description is given for a particular method for the manufacture of such a product and a manner in which it may be used, it being understood, however, that the scope of the invention is not limited to the therein described manner of performance or the proportional quantities.

Example.—280 parts by weight of a fatty alcohol mixture (first runnings of the fatty alcohol mixtures obtained by catalytic reduction of cocoa-fat and distilling up to 130° C. at 3 mm. pressure of mercury) are heated for 16 hours to 115–120° C. in an open vessel together with 150 parts by weight of epichlorhydrine and 6 parts by weight of concentrated sulphuric acid. The reaction mixture is freed from sulphuric acid by boiling with water and is purified from by-products by fractional distillation. The main fraction boiling between 150 and 195° C. at 12 mm. pressure of mercury contains 13.2% of chlorine and is re-

acted at 130° C. in well-known manner with the calculated amount of sodium sulphite in a con-

centrated aqueous solution. The thus obtained reaction product is clearly soluble even in hard water at 35 to 40° C. and it develops a stable lather.

5. When the product obtained in accordance with the procedure of the above example is used for wetting-out of makopearlyarn, the goods are brought into a bath containing 0.1% of this product. The wetting-out occurs immediately and the 10 materials are readily penetrated by the subsequent treatment baths (bleaching-, dyeing baths and the like).

For cleansing of woolen piece goods one employs a bath which contains about 1.5 g. of 15 the aforementioned product per litre of water. If there are considerable quantities of free fatty acids in the wool, an admixture of ammonia or soda is recommended. Material which has been dried with dye stuffs sensitive to alkali, can be 20 treated in the same bath, if the latter has previously been rendered acid by an addition of formic acid. The indicated cleansing bath develops an excellent detergent effect and imparts a soft and pliant feel to the thus treated material. 25 For cleansing of raw wool one usefully employs a 0.2% bath with 0.1% cyclo-hexanol and 0.1% of the above mentioned high molecular ether of the hydroxylalkylsulphonic acid. By this the material is perfectly degreased. The presence of 30 lime soap in the wool does no harm in the present case, since it is likewise dispersed by the bath.

What I claim is:—

1. The method of producing a di-alkyl ether sulfonic acid salt which comprises preparing an 35 ether from a glycidic and a fatty alcohol having 8 or more carbon atoms in the molecule, and reacting a chloride of said ether in which the chlorine is attached to the glycidic radical of said ether with sodium sulfite to produce a sodium salt of 40 the sulfonated ether.

2. The method of producing a dialkyl ether sulfonic acid salt which comprises reacting epichlorhydrine with a fatty alcohol having 8 or more carbon atoms in the molecule in the presence of 45 sulfuric acid and converting the product with sodium sulfite to produce sulfonic compounds.

3. A wetting and cleansing textile treatment agent consisting of an ether having in its formula on one side of the etherial oxygen atom a fatty alkyl radical containing 8 or more carbon atoms and on the other side a radical of an hydroxy propane sulfonate salt, the cation of which is an alkaline metal imparting water solubility 55 properties to the ether.

4. As wetting, washing, cleansing, lathering and dispersing agents, the products of the formula

60 wherein R is an alkyl radical of at least 8 carbon atoms and X is hydrogen or an alkali metal.

5. A wetting and cleansing textile treating agent comprising the sulfonate of dihydroxy propane etherified with an alcohol radical selected from the group consisting of fatty alcohol radicals of at least 8 carbon atoms and naph-

thenic alcohol radicals, the sulfuric acid radical being joined to the propane radical.

6. Wetting and cleansing textile treating agents consisting in neutral sulfonates of ethers of glycerine with fatty alcohols having at least 8 carbon atoms, the sulfuric acid radical being joined to the glycerine radical. 5

7. The method of preparing salts of sulfuric acid derivatives of ethers comprising forming a chloride of an ether by a process which includes reacting a glycidic with a fatty alcohol having at least 8 carbon atoms in the molecule, said chlorine atom being joined to the glycidic radical of the ether, then sulfonating said ether through replacement of the chloride radical with a sulfonate radical by reacting with a sulfite salt. 10 15

8. Wetting and cleansing textile treating agents consisting of alkali metal salts of sulfuric acid derivatives of ethers of glycerine with fatty alcohols corresponding to the fatty acids contained 20 in an oil selected from the group consisting of cocoanut and palm kernel oils, the sulfuric acid radical being joined to the glycerine radical.

9. An ether of an alkyl radical with dihydroxy propyl sulfonic acid in which the alkyl radical joins through an oxygen atom of one of said hydroxy groups and is derived from cocoanut oil by reduction of the fatty acids therein to the corresponding fatty alcohols. 25

10. Alkyl ethers of poly hydroxy alkyl sulfonic acids in which the alkyl radicals on the one hand have more than 8 carbon atoms and are derived from and correspond to the mixture of fatty alcohols obtained by reduction of an oil selected 30 from the group consisting of cocoanut and palm kernel oils and the poly hydroxy alkyl radicals on the other hand are derivable from and corresponding to the glycerine radical, the sulfuric acid radical being joined to the glycerine radical. 35

11. The process of producing alkyl ethers of 40 poly hydroxy alkyl sulfonic acids which comprises reducing cocoanut oil to alcohols, reacting a mixture of such alcohols with epichlorhydrine in the presence of sulfuric acid and reacting the resulting product with sodium sulfite to produce the 45 sulfonic acid.

12. The compound of the formula

where R represents an alkyl group containing 50 one or more hydroxy groups at least one of which is etherified with an hydroxy fatty alcohol having 8 or more carbon atoms in the molecule and where X is a member of the group consisting of an H atom and a cathion of a neutralizing agent. 55

13. The compound of the formula

where R represents an alkyl group containing 60 one or more hydroxy groups one of which is etherified with a hydroxy stearyl and where X is a member of the group consisting of an H atom and a cathion of a neutralizing agent. 65

RICHARD HUETER.

CERTIFICATE OF CORRECTION.

Patent No. 2,094,489.

September 28, 1937.

RICHARD HUETER.

It is hereby certified that error appears in the printed specification of the above numbered patent requiring correction as follows: Page 2, first column, line 19, for "dryed" read dyed; and second column, line 62, claim 13, after "stearyl" insert alcohol; and that the said Letters Patent should be read with these corrections therein that the same may conform to the record of the case in the Patent Office.

Signed and sealed this 8th day of February, A. D. 1938.

Henry Van Arsdale,
Acting Commissioner of Patents.
